UNITED STATES PATENT OFFICE

GUS F. LENK, OF DALLAS, TEXAS

CHARGING APPARATUS FOR INCINERATORS

Application filed June 20, 1927. Serial No. 200,232.

This invention relates to new and useful improvements in charging apparatuses for incinerators.

One object of the invention is to provide a charging apparatus, whereby a bulk charge of waste may be introduced into the fire chamber of the incinerator without admitting cold air and whereby the succeeding charge awaiting displacement into the fire chamber forms a plug so that the waste is subjected to a drying action and the charging ram is protected from the fire.

Another object of the invention is to provide a charging means and method, whereby an adequate supply of waste may be accumulated in a charging hopper and chute to feed an incinerator over a period of hours, thus making for economy in operation and service.

A construction designed to carry out the invention will be hereinafter described, together with other features of the invention.

The invention will be more readily understood from a reading of the following specification and by reference to the accompanying drawings, in which an example of the invention is shown and wherein:

Fig. 1 is a longitudinal vertical sectional view of an apparatus constructed in accordance with my invention with parts in elevation.

Fig. 2 is a transverse sectional view taken on the line 2—2 of Fig. 1, and

Fig. 3 is a transverse sectional view taken on the line 3—3 of Fig. 1.

In the drawings the numeral 10 designates the rear wall of the fire chamber of an incinerator. In the chamber is a drying table 11 inclined toward the fire grate, while above the table is the arch or roof 12. A similar structure will be found in my Letters Patent No. 1,561,734 issued Nov. 17, 1925, but the invention is not to be limited to this particular incinerator.

In the wall 10 is a rectangular opening 13 having a liner casing 14. The bottom of the liner casing is shown flush with the top edge of the table. A rectangular chute 15 is suitably secured to the outer face of the wall so as to register with the lining which forms a continuation and part of the chute.

A large hopper 16 having an inclined back wall 17 and inclined side walls 18 is provided with a vertical front wall 19 secured to the face of the wall 10. The hopper has an open bottom discharging into the chute. 55

A ram including a rectangular plunger head 20 is provided. The head 20 has a sliding fit in the chute. The ram also includes an apron or closure hood 21 attached to the rear side of the head. Flanged guides 22 are secured along the lower extremity of each side wall 18 and the head and apron slide under these guides. Teeth 23 are provided on the front upper end of the head, so as to cut off the charge as the head passes under the wall 19 in entering the liner casing 14. 60 65

The apron 21 is long enough to completely close the bottom of the hopper when the ram reaches the end of its forward stroke and the head is within the liner casing. The rear or back stroke of the ram is limited by the engagement of the head 20 with a stop 24 on the floor of the chute. 70

The bottom of the apron is open for reception of a standard 25 on which the cylinder 26 of the ram is secured. The rear end of the cylinder is fastened to a post 27 or other support. A fluid pressure supply pipe 28 is connected to the rear end of the cylinder. A tubular plunger 29 extends through a stuffing box 30 at the forward end of the cylinder. A packing ring 31 in the box is compressed about the plunger by a gland nut 32. The forward end of the plunger is bolted to the head 20. 75 80 85

It will be seen that when fluid under pressure is admitted from the pipe 28 into the cylinder 26, the plunger 29 will be expelled and the head 20 and apron 21 thus driven forwardly through the chute 15 and into the liner casing 14. After the fluid pressure within the cylinder has been released, some means for returning the parts must be provided. As an illustration, I have shown a flexible connection 33 attached to the head 20 and passing over a pulley 34. The connection has a weight 35 secured to its lower end. This arrangement will return the ram. 90 95

In the handling of waste, such as garbage, rubbish, offal and the like, in cities, it is im- 100

practical and too expensive to have the trucks or bearing vehicles to come to the incinerator at frequent intervals or to regulate the time when they do come; therefore, it is customary for the vehicles to collect waste during a long period of hours and come to the incinerator at the end of the period. A congestion of vehicles results and each must wait its turn to unload into the incinerator.

- 10 It will be appreciated that by providing adequate hoppers at the incinerator plant, the waste may be dumped into these hoppers and then fed to the fire chambers as needed, thus releasing the vehicles and permitting a 15 more efficient and economical operation. After the first charges of waste have been fed through the chute, the liner casing 14 will be constantly plugged, the plug being displaced onto the table by the next charge. 20 The plug prevents cold air entering the fire chamber and the heat tends to evaporate the moisture in said plug. This with the drying action on the table 11 makes for better combustion, and more thorough consumption. 25 If the waste is wet it will tend to pack in the chute, thus making even a better plug.

Various changes in the size and shape of the different parts, as well as modifications and alterations, may be made within the 30 scope of the appended claims.

What I claim, is:

1. In an incinerator charging apparatus, the combination of a chute, a hopper feeding thereto, a plunger head disposed to traverse 35 the chute and having an extended apron formed with an open lower portion, a support extending within the apron through said open portion, a fluid pressure cylinder carried by said support and open at its end next the chute, a fluid inlet at the opposite end of said cylinder, a tubular piston within the open end of the cylinder and connected to said head, and a tensioned connection to return the piston to the interior of its cylinder. 40
2. In an incinerator charging apparatus, the combination with the fire chamber of an incinerator having a charging opening in one of its upright walls, of a chute registering with the opening of the fire chamber and having an outward extension, a liner casing 50 in said opening forming a continuation of the chute, a hopper discharging into the chute, a head having teeth traveling through the chute beneath the hopper, an apron carried by the head and having its lower portion open and supported by said extension, a fluid pressure actuated cylinder having a piston for driving the head through the chute to the charging opening, a support for the 55 cylinder extending through the open portion of the apron, and means for returning the head from the charging opening. 60

In testimony whereof I affix my signature.
